LOUISIANA

OIL HEATER

Application filed November 27, 1926. Serial No. 151,154.

This invention relates to oil treating methods and means, and has for an object the provision of an apparatus effective to heat crude oil in order to facilitate its circulation through distributing pipes or pipe lines, the said invention also being intended to improve the condition of oil prior to its being delivered to a pipe line.

The invention is adapted for use in association with a gun barrel or a tank, and is intended to circulate the crude oil with hot water or treating compound through said tank and heater, the heated mixture being discharged from the heater into the top of the gun barrel or tank. The circulation is usually continued for a period of time which will result in separating the oil from the water and placing the oil in condition for a pipe line run. By reason of the presence of the invention in association with the parts mentioned, the equipment necessary to change the quality of the oil and reduce it to a condition where it can be run in a pipe line is of simple nature, as compared with boilers, pumps and other lines which are now commonly used in this art.

It is an object of this invention to produce a heater associated with circulating pipes leading to and from a tank or gun barrel, the same being effective to produce the results indicated through an efficient and comparatively inexpensive process.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

Figure 1 illustrates a sectional view of a heating apparatus embodying the invention;

Figure 2 illustrates a sectional view of the said device on the line 2—2 of Fig. 1.

The heater proper, in the present embodiment of the invention, comprises an internal pipe 5 and a jacket 6 mounted in spaced relation to each other to produce an annular

chamber 7. The space between the pipe and jacket is closed at the ends by annular rings or heads 8 and 9, and the said pipe and jacket are stayed and held in spaced relation to each other between the heads by members 10, such as rivets. A smoke uptake or stack 11 communicates with the firing chamber which is contained within the pipe 5, and the jacket has a head or door 12 at one end which encloses the chamber 13 with which the stack 60 communicates so that heat and products of combustion passing through the pipe 5 escape through the stack. This element 12 is provided and made removable for the purpose of permitting access to the interior for making repairs to flanges or the like.

The jacket 6 has a manhole 14 with a suitable closure 15 of known construction, which should be effective to close the manhole with a leak-proof joint.

The jacket 6 has nipples or pipe connections 16, 17 and 18, the latter of which is intended as a drain for washing out the annular chamber and discharging sediment or the like, which may tend to foul the interior thereof. The nipple 16 is for the connection of a suction line or pipe 18' provided with a check valve 19, for the purpose of conducting salt water or treating compound and oil from the gun barrel or tank to the heater in order that it will circulate in the heater through the annular channel. The nipple 17 is connected to a discharge line 20 having a check valve 21 to conduct the hot salt water or treating compound and oil from the heater to a flume on top of a gun barrel or stock tank. As such gun barrels or stock tanks are well known in the art, it is believed unnecessary for an understanding of one skilled in the art to illustrate a conventional type thereof.

The check valve on the suction line is to maintain hot salt water or treating compound within the circulating system and prevent it from returning to the bottom of the gun barrel, whereas the check valve on the discharge line is to prevent back pressure from the gas line, from forcing hot salt water or treating compound back into the heater. The check valve 24 on the gas line is to pre-

vent the entrance of hot salt water or treating compound into the gas line.

A gas line 22 is associated with the apparatus and a pipe 23 connects the gas line and the discharge line 20. The pipe 23 is connected to the discharge line ahead of the check valve 21 and the pressure in the gas line is employed for furnishing pressure to push the hot salt water or treating compound to the flume on top of the gun barrel or tank. A check valve 24 is in the pipe 23 to prevent hot salt water or treating compound from gaining access to the gas line.

We claim:

15. 1. An oil heater comprising a heat conducting pipe and a jacket held in spaced relation to each other with a channel therebetween, means for closing the ends of the channel, a pipe communicating with the interior of the heater near one end and adapted to communicate with a source of oil supply, a pipe communicating with the annular channel near the other end for returning oil to the said oil supply, and pressure augmenting means communicating with the second mentioned pipe and adapted to be connected for delivering gas under pressure to force the oil back to the oil supply.
20. 2. An oil heater comprising a heat conducting pipe and a jacket held in spaced relation to each other with a channel therebetween, means for closing the ends of the channel, a pipe communicating with the interior of the heater near one end and adapted to
25. communicate with a source of oil supply, a pipe communicating with the annular channel near the other end for returning oil to the said oil supply, a check valve in said pipe, a pipe communicating with the last mentioned pipe in a location beyond the check valve, the said pipe being adapted to deliver gas under pressure to force the oil back to the said oil supply.

GEORGE B. REEGER.
